SEWING MACHINE

Henry C. Nissen, Stratford, and James E. Ackerman, Devon, Conn., assignors to The Singer Manufacturing Company, Elizabeth, N. J., a corporation of New Jersey

Application January 8, 1942, Serial No. 425,956

8 Claims. (Cl. 112—206)

This invention relates to sewing machines and more particularly to sewing machines which are fitted with work-guides, especially such as binders, folders and the like.

In stitching a binding or a plain strip of fabric to a body material it has heretofore been the practice to utilize a sewing machine fitted with an appropriate conventional stationary strip-guide mounted upon the machine cloth-plate directly in front of the stitching mechanism. Such sewing machines have used, in this type of stitching operation, various types of feeding mechanisms including the lower four-motion, the upper four-motion and the needle-feed. However, in each case, no matter which type of feeding mechanism was used, the strip material was pulled through the work-guide by means of a feeding mechanism, and as the work-guide offers resistance to the passage of the strip, a tension is thereby produced within the strip. This tension is normally not objectionable when the strip is of the usual woven wool, silk or linen type of fiber which is naturally non-elastic and non-adherent. However, when a strip of material is used having elastic and adhering properties, such as rubber or one of the synthetic materials, the work-guide through which the strip is pulled by the feeding mechanism introduces a drag on the strip to stretch it a substantial degree. The strip material is therefore stitched to the body-material while stretched and the resultant product becomes puckered as the elastic strip recovers its initial or unstretched condition.

It is therefore a primary object of the present invention to produce a sewing machine which will overcome the puckering effect incidental to stitching strips, binding tapes and the like having elastic and adhering properties.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

The several features of the present invention will be clearly understood from the following description and accompanying drawings in which—

Fig. 1 is a front sectional elevation of a sewing machine embodying the present improvement.

Fig. 2 is a left end elevation of the machine shown in Fig. 1.

Fig. 3 is a top plan view of the work-arm, work-guide, presser-foot and feed-foot.

Fig. 4 is a view similar to that of Fig. 3, but showing the work-guide in a different position.

Fig. 5 is a fragmentary vertical section taken substantially along line 5—5 of Fig. 4.

Fig. 6 is a perspective view of a piece of body material being bound by the present machine.

Fig. 7 is a transverse sectional view of a finished portion of a product and taken substantially along line 7—7 of Fig. 6.

Referring to the drawings, the sewing machine comprises a frame including a bed 1 from which rises the standard 2 and the overhanging bracket-arm 3 terminating in the hollow head 4. Journaled in suitable bearings provided in the standard 2 and bracket-arm 3 is the main or needle-bar actuating shaft 5, carrying at one end the usual hand- and belt-wheel 6. The main-shaft 5 also carries the pulley 7, connected by means of the clip belt 8 with the pulley 9 secured upon the loop-taker-actuating shaft 10, suitably journaled in bearings provided in the bed 1 and carrying the loop-taker 11.

At its forward end, the main-shaft 5 carries a crank 12 to which is secured the crank-stud 13 connected by the link 14 to the needle-bar 15 carrying the eye-pointed needle 16. By means of this construction, endwise reciprocatory movements are imparted to the needle-bar 15 which is journaled in vertically aligned apertures formed in an oscillating feed-frame 17.

The feed-frame 17 is mounted to oscillate upon oppositely arranged pivotal bearings comprising the fulcrum stud 18 threaded into the overhanging arm 3, and pivot-pin 19, secured by the screw 20 in the arm 21 of said feed-frame 17 and entering an aperture 22 formed in the bed 1. To the forward end of the arm 21 of the feed-frame is rigidly secured by means of a screw 34 the feed-bar 23 having a raised serrated portion or feed-dog 24 and a needle-aperture not herein shown. The feed-frame 17 receives its oscillating movements from an adjustable feed-eccentric 25 mounted on the main shaft 5, embraced by an axially shiftable strap 26 which is adapted to be entered by a pin 27. The pin 27 is formed or otherwise provided at its lower end with an eccentric portion 28 which is adjustably secured by means of the screw 29 in the apertured ear 30 provided on the feed-frame 17. Adjustment of the eccentric portion 28 regulates the position of the needle relative to the axis of the loop-taker shaft 10. The eccentric 25 may be adjusted to vary the feed by means of the knob 31 in a man-

ner well known, and fully shown and disclosed in the U. S. patent to W. F. Dial et al., No. 718,988, January 27, 1903. For a more complete disclosure of the present sewing machine mechanism reference may be had to the U. S. patent to Albert Rontke, No. 989,538, April 11, 1911.

Pivottally mounted upon the feed-bar 23 on a screw 32 disposed forwardly of the axis 19 of oscillation of the feed-frame 17, is the supporting bar or base 33 for a work-guide in the form of a transverse binder 35 adjustably secured to said supporting bar 33 by screws as 36. The axis-screw 32 is secured directly in the feed-bar 23. The cloth-plate 37 secured directly to the bed 1, carries by means of screws 38, a stationary bracket 39 which is provided with a fulcrum-pin 40. A slightly elongated aperture 41 provided in the bar 33 receives the fulcrum-pin 40 about which the bar 33 and consequently the binder 35 swings when actuated by the feed-frame 17 through the medium of the axis-screw 32. It is to be understood, therefore, that since the axis-screw 32 is secured to the feed-bar, the axis-screw receiving portion or that end of the bar 33 remote from the feed-dog 24, will oscillate substantially in unison with said feed-bar. The forward portion of the bar 33, carrying the binder 35 will, because of the position of the fulcrum-pin 40, oscillate in opposition to the direction of feed-dog movements.

The strip guide herein shown is of that well known type styled the English binder, but it is to be understood that the invention is not limited to this type of work-guide. It will be observed that the binder-head is partially cut away to permit positioning it closely adjacent at the needle 16 when the binder is oscillated to its extreme position in the direction of work-feed.

Moving laterally with the feed-dog 24 is the top feed-foot 42 carried by the feed-foot bar 43 journaled for vertical movement in the feed-frame 17. The vertical reciprocations of the feed-foot 42 alternate with like movements of the presser-foot 44, the alternate reciprocations of these elements being caused by mechanism such as fully shown and described in the patent to Rontke, No. 989,538, before referred to or by any other suitable mechanism of a like character which is well known in the art. The feeding foot 42 is partly cut away as at 45 to permit the close adjustment of the binder relative to the needle. The binding tape 46 is led from a suitable supply source to the binder 35 which folds the tape about the edge of a body material 47 as best shown in Fig. 6. Fig. 7 illustrates a cross section through the finished product showing the relative positions of the body-material 47, the tape 46, a backing tape 48 and the stitches 49. The backing is also guided by the binder 35.

In the operation of the sewing machine and during the feeding movement of the needle, the binding is held by the needle positively in position upon the margin of the body-fabric, the feed-foot 42 contacting with the work and the presser-foot 44 being raised. The work is thus clamped between the lower feed-dog 24 and the upper feed-foot 42, and these elements with the needle move in unison to feed the work while the binder is moved oppositely to these movements thereby drawing a length of binding through the binder during the work-advancing movement of the feeding instrumentalities. During the return movements of the feed, the feed-foot 42 is raised, the presser-foot 44 engages the work and the binder vibrates toward the feeding

instrumentalities before the work-feeding needle penetrates the work. This forward movement of the binder has the effect of relaxing the binding tension induced by the action of drawing said binding through the binder. The needle now pierces the work including the binding which is unstretched and hence does not pucker the body fabric. The stitches are thus produced in the tape when it is in a normal and untensioned condition. It is to be understood therefore, that although tension is induced in the binding when the feeding mechanism is advancing the work and the binder is vibrating in a direction opposite to the feeding movements, this tension can in no way effect that portion of the work being stitched as it is positively clamped by the feed-dog, feed-foot and the needle.

The present machine therefore is particularly adapted for sewing binding tapes and the like work having elastic properties as it provides a positive control over the work at all times, and due to its novel action it obviates the puckering effect incidental to stitching a tensioned elastic tape to a body fabric.

Having thus set forth the nature of the invention what we claim herein is:

1. In a sewing machine, the combination with an endwise reciprocating needle, an upper feed-foot, means to impart feed-and-return movements to said needle and said upper feed-foot, a lower feed-dog, and means for actuating said lower feed-dog in synchronism with said upper feed-foot, of a work-guide, and means for actuating said work-guide in opposition to the feed-and-return movements imparted to said upper feed-foot.

2. In a sewing machine, the combination with an endwise reciprocating and laterally movable needle, and means for imparting said movements to the needle, of a work-guide, and means for actuating said work-guide in opposition to said lateral movements of the needle.

3. In a sewing machine, in combination, a needle, means for endwise reciprocating said needle, a feed-dog, a binder, and means for imparting lateral movements to said needle and feed-and-return movements to said feed-dog whereby the lateral movements of said needle and the feed-and-return movements of said feed-dog remain substantially in parallelism, said last named means imparting bodily movements to said binder in opposition to the feed-and-return movements imparted to said feed-dog.

4. In a sewing machine, in combination, an endwise reciprocating needle, a rotary shaft for reciprocating said needle, a feed-dog, means connected to said rotary shaft for imparting feed-and-return movements to said feed-dog, a work-guide, and connections intermediate said means and said work-guide for imparting bodily movements to said work-guide in opposition to the feed-and-return movements imparted to said feed-dog.

5. In a sewing machine, in combination, an endwise reciprocating needle, means for reciprocating said needle, means for imparting lateral movements to said needle, a feed-dog, a feed-dog actuating means to impart feed-and-return movements to said feed-dog whereby said feed-dog will move substantially in parallelism with the lateral movements of said needle, a work-guide, means to support said work-guide, and connections intermediate the work-guide and the feed-dog actuating means for moving said work-

guide in opposition to those movements imparted to said feed-dog.

6. In a sewing machine, in combination, a frame, a feed-dog, feed-actuating mechanism to impart a work-advancing stroke to the feed-dog during its cycle of operations, a work-guide, stationary means carried by said frame, said work-guide pivotally engaging said stationary means, and means connecting said feed actuating means and said work-guide for shifting the same about said stationary means in a direction opposite to the direction of feed of the work-passing through said work-guide during the work-advancing stroke of the feed-dog.

7. In a sewing machine, in combination, a frame, a feed-dog, feed-actuating mechanism to impart feeding movements to said feed-dog, a bar sustained by and disposed substantially longitudinally of said frame, a work-guide secured upon the end of said bar adjacent to said feed-dog, means connecting said feed-actuating mechanism with the end of said bar remote from said

5 feed-dog for actuating that end of the bar in unison with said feed-dog, and stationary fulcrum means carried by said frame, said bar member pivotally engaging said stationary fulcrum means at a point on the bar between said feed-dog and said end of the bar remote therefrom.

8. In a sewing machine, in combination, a frame, work-feeding mechanism having a work-advancing stroke during its cycle of operation, a base bar sustained by said frame, a work-guide secured upon one end portion of said base bar, stationary means carried by said frame, said base bar pivotally engaging said stationary means at a point between the ends of said bar, and means connecting said work-feeding mechanism with the end of said bar remote from said work-guide for actuating said work-guide in a direction opposite to the direction of feed of the work and during the work-advancing stroke of said work-feeding mechanism.
